UNITED STATES PATENT OFFICE.

WILL C. NEAHR, OF DENVER, COLORADO, ASSIGNOR TO THE PROTECTIVE SIGNAL MANUFACTURING COMPANY, OF DENVER, COLORADO, A CORPORATION OF COLORADO.

PLUG-SOCKET.

1,159,701.

Specification of Letters Patent.

Patented Nov. 9, 1915.

Application filed September 28, 1914. Serial No. 863,960.

To all whom it may concern:

Be it known that I, WILL C. NEAHR, a citizen of the United States, residing at Denver, in the county of Denver and State of Colorado, have invented new and useful Improvements in Plug-Sockets, of which the following is a specification.

The present invention relates more particularly to extension plug sockets, particularly intended for use in connection with electric lamps or other electrical devices arranged in series. Thus, for example, in car pits, it is the usual practice to employ a plurality of incandescent lamps arranged in series. It is often desirable to employ an extension plug in this car-pit work, and it is the usual practice to remove one of the lamps of the series and insert the extension plug in its place. To do this properly, the current should first be cut off from the lamps, but as this is more or less trouble, more often the workman merely removes one of the lamps from the circuit and introduces the plug. As a result, arcs are created, which are apt to burn out the contact elements.

One of the primary objects of the present invention is to provide a plug-receiving socket which may be so connected up to the lamp series or the like that the introduction of a plug into the socket automatically cuts out one of the lamps when the plug is being seated, thereby eliminating both the annoyance of first opening the circuit and the danger of arcs if it is not done.

A further and important object is to provide a structure that is exceedingly simple and practicable, and one that will take the standard plug or plug fittings.

An embodiment of the invention is illustrated in the accompanying drawings, wherein:

Figure 1 is a plan view of the preferred form. Fig. 2 is a sectional view on the line 2—2 of Fig. 1. Fig. 3 is a sectional view on the line 3—3 of Fig. 1. Fig. 4 is a diagrammatic view indicating the manner of connecting the device in a circuit.

Similar reference numerals designate corresponding parts in all the figures of the drawings.

In the embodiment disclosed, a base 5 is employed, which is preferably in the form of an integral block of porcelain or other insulating material, this block being pro-

vided on its outer face with a central integral socket element 6.

Formed in the outer face of the base 5, and extending from one corner to the other, is a diagonal slot 7 that extends but part 60 way through the block, and has reduced end portions forming seats 8. The block furthermore has a slot 9 in its rear face that extends at right angles to the slot 7 from one corner of the block to the central portion 65 thereof beneath the socket element 6.

Located in the said socket element 6 is a plug-receiving shell 10, which is preferably of the standard screw type, having an open bottom and inturned bottom flanges 11 that 70 rest upon the bottom of the socket element on opposite sides of the portion of the slot 7 which intersects the same. Through one of these flanges is passed a holding bolt 12, the nut 13 of which is located in the inner 75 end of the slot 9. In said slot 9 is also arranged a conducting strip 14, the inner end of which is secured to the other of the in-turned flanges 11 by a screw 15. The outer end of the strip 14 is engaged with a holding bolt 16 that passes transversely through the corner of the base or block 5, its upper end being located in a recess 17 in the outer face of the block, said bolt forming a terminal binding post. 80

Arranged in the outer slot 7 is a make-and-break device, consisting of a pair of leaf springs 18 and 19. The spring 18 is mounted on one of the seats 8, and is held in place by a bolt 20 forming a binding post. The 90 other spring 19 has one end located on the other seat 8, and is held in place by a bolt 21, also forming a binding post. The opposite end of the spring 19 underlaps the free end of the spring 18 and it furthermore has 95 an intermediate outwardly bowed portion 22 that projects into the inner end of the socket element 6 and the plug-receiving shell 10.

One method of connecting the device in a lamp series, is indicated in Fig. 4, wherein the circuit which is designated generally by the reference numeral 23, includes the binding posts 16 and 20 being connected thereto by the wires 24 and 25. The binding post 21 is also connected in the series, as 100 shown by the wire 26. As long as there is no plug in the socket shell 10, the spring 19 will be in contact with the spring 18 and a circuit will thus be completed through all the lamps. If, however, an extension plug, 110

indicated at 27 in Fig. 4, is screwed into the socket shell 10, the spring 19 will be disengaged from the spring 18, thus opening the circuit through said springs, but at the same time, a circuit will be established through the extension 28, cutting out the central lamp of the series in the circuit 23.

From the foregoing, it is thought that the construction, operation and many advantages of the herein described invention will be apparent to those skilled in the art, without further description, and it will be understood that various changes in the size, shape, proportion and minor details of construction 15 may be resorted to without departing from the spirit or sacrificing any of the advantages of the invention.

Having thus fully described my invention, what I claim as new and desire to secure by Letters Patent, is:

1. In a device of the character set forth, the combination with a base having an outstanding socket element and a slot in the base that intersects the bottom of the socket element, of a plug holding shell in the socket element, and coacting make-and-break elements located in the slot, one of said elements being disposed in the path of a plug introduced into the shell.
2. In a device of the character set forth, the combination with a base having an outstanding socket element and a slot in the outer face of the base that extends beneath the socket element, of a plug holding shell in the socket element, and coacting make-and-break elements located in the slot, one of said elements being a spring having a portion projecting outwardly into the inner end of the socket element and into the path 40 of a plug introduced into the shell.
3. In a device of the character set forth, the combination with a single piece base having an integral outstanding socket element and a transverse slot in its outer face 45 that extends beneath the socket element and intersects the bottom thereof, of a screw shell secured in the socket element, and coacting make-and-break elements mounted on the base, one of said elements being disposed longitudinally of the slot and having an outstanding portion projecting above the same into the inner end of the screw shell.
4. In a device of the character set forth, the combination with a single-piece base

having an integral outstanding socket element and a transverse slot in its outer face that extends beneath the socket element and intersects the bottom thereof, of a screw shell secured in the socket element, coacting make-and-break elements mounted on the base, one of said elements being disposed longitudinally in the slot and having an outstanding portion projecting above the same into the inner end of the screw shell, and fastening devices for the make-and-break elements located at opposite ends of the slot and constituting terminal binding posts.

5. In a device of the character set forth, the combination with a base having a socket element, a groove in its outer face intersecting the bottom of the socket element, and a groove in its rear face, of a plug receiving shell located in the socket element, a conducting strip in the rear groove, a holding device for the shell engaging the strip and shell and passing through the base, and make-and-break elements, one of which is located in the outer groove, and has a portion projecting outwardly into the plug-receiving shell and into the path of movement of a plug inserted thereinto.

6. In a device of the character set forth, the combination with a single-piece base having an outstanding integral socket element, a transverse groove in its outer face extending beneath the bottom of the socket element, and an angularly disposed groove in its rear face, of a screw plug receiving shell located in the socket element, a conducting strip located in the rear groove, a binding post extending through the base and engaged with the strip, a fastening device for the screw shell disposed at one side of the outer groove and engaging said strip, contact elements located in the outer groove, one of said elements being a spring and having an outwardly bowed portion extending into the inner end of the screw shell, and binding posts securing the contact strips in position.

In testimony whereof I have hereunto set my hand in presence of two subscribing witnesses.

WILL C. NEAHR.
